UNITED STATES PATENT OFFICE.

JAMES G. MACLAREN, OF SYRACUSE, NEW YORK, ASSIGNOR, BY MESNE ASSIGNMENTS,
TO THE LAMSON COMPANY, A CORPORATION OF MASSACHUSETTS.

PNEUMATIC DISPATCH CARRIER.

Application filed October 11, 1922. Serial No. 593,687.

This invention relates generally to carrier devices for use with pneumatic dispatch apparatus.

The principal object of the invention is to provide an improved carrier device particularly adapted for the transportation of memorandum slips, reference data and other matter involving the use of slips or sheets of paper from one place to another through the conveyor tubes of a pneumatic dispatch system.

The invention includes the provision of a slip holder attached at its ends to terminal buffer members, and a coating hinged 15 clamping or closure member arranged to be moved into or out of slip holding relation to the slip holder through relative rotation of the terminal buffer members. Other features of the invention include the provision of 20 sight openings in the holder and the closure member through which data on the contained slip may be viewed. Still other features of the invention will be hereinafter referred to.

In the drawings in which a number of preferred embodiments of the invention have been selected for illustration,

Figure 1 is a view in side elevation and partly broken away of a dispatch carrier embodying the invention.

Figure 2 is a view in cross section of the carrier shown in Figure 1 in closed condition.

Figure 3 is a view similar to Figure 2 showing the carrier in open condition.

Figure 4 is a view in perspective of an opening device forming part of the carrier construction.

Figure 5 is a view in cross section of a modified form of the carrier showing the carrier in closed condition.

Figure 6 is a view similar to Figure 5 showing the carrier in open condition.

Figure 7 is a view in perspective and partly broken away of one end of the closure member shown in Figures 5 and 6.

Referring to the drawings for a more detailed description of the invention, a slip holder member 5 is shown which preferably consists of a flat and shallow receptacle, rectangular in outline, and particularly adapted to hold a folded memorandum slip of the type used in department stores and other business organizations. The shallow slip holder 5 is attached at its ends in any desired manner to a pair of disc members 6 which

support terminal buffer members 7 and 8 of 55 a known type commonly formed of felt. The buffer 8 is fixed to the adjacent member 6, while the buffer 7 is rotatably connected to its disc 6.

A closure member or clip 9 is hinged along 60 one edge to the rearward extremity of the slip holder 5 and is adapted in its closed position to lie within the opening of the slip holder substantially flush with the upper edge of the front wall member 10 of the slip 65 holder. The closure member 9 is preferably provided with an elongate opening or openings 11 through which identifying data displayed on a contained slip may be viewed. The slip holder member 5 may also be provided with an opening 12 through which a finger tip may be passed for removing a slip 70 from the holder, and a suitable marker 13 preferably is affixed to the slip holder 5.

In order to provide a ready means for 75 operating the hinged closure member, an inwardly projecting finger or lug 14 is arranged on the right-hand terminal member 7 for engagement with the under side of the adjacent end portion of the clip or closure 80 member 9. The terminal member 7 being rotatably mounted, it will be seen that the rotation of the terminal buffer 7 to the right causes the finger 14 to lift the closure member 9 from its closed to an open position with 85 relation to the slip holding receptacle 5. In order to bring the closure to its closed position the buffer member 7 is rotated in the opposite direction whereupon, in the form of the invention shown in Figure 1, a 90 spring 15 moves the closure member 9 to its closed position, the member 9 following the movement of the finger 14.

In the form of the invention shown in Figure 5 of the drawings the spring 15 is 95 dispensed with and the operating finger is used to move the closure member to both its closed and its opened positions. This function is achieved by the provision of a slotted guide member 16 on the end of the closure member 9, the slot 17 receiving the operating finger 14 as will be clear.

It will be seen that I have provided a carrier device which is particularly adapted to hold and transport paper slips, folded or not folded, in which information is contained and which presents identifying data on the slip in position to be easily viewed 105

without opening the holder, and which can be readily opened or closed as occasion requires.

What I claim is:—

- 5 1. In a carrier for pneumatic dispatch apparatus, a relatively flat slip holder, buffer members attached to the slip holder, and a clip member having a hinged connection with one side of the holder and cooperating therewith to hold a memorandum slip.
- 10 2. In an elongate carrier for pneumatic dispatch apparatus, a shallow slip holding receptacle, buffer members attached to the ends of the receptacle, and a closure member having a hinged connection with the receptacle, the axis of the hinge being substantially parallel to the axis of the carrier.
- 15 3. In a carrier for pneumatic dispatch apparatus, a shallow elongated rectangular slip holding receptacle, buffer members attached to the ends of the receptacle, and a closure member hinged to one side of the receptacle.
- 20 4. In a carrier for pneumatic dispatch apparatus, a slip holding member, buffer members attached to the ends of the holder, one of said buffer members being rotatably mounted, a clip member having a hinged connection with said slip holding member, and operating means for said hinged member carried by said rotatable buffer member.
- 25 5. In a carrier for pneumatic dispatch apparatus, a slip holding receptacle, buffer members attached to the ends of the receptacle, one of said buffer members being rotatably mounted, a closure member having a

hinged connection with said slip holding receptacle, and operating means for said closure member carried by said rotatable buffer member.

40 6. In a carrier for pneumatic dispatch apparatus, a relatively flat slip holding member, buffer members attached to the ends of the holder, one of said buffer members being rotatably mounted, a clip member having a hinged connection with said slip holding member, and operating means for said clip member actuated by said rotatable buffer member.

45 7. In a carrier for pneumatic dispatch apparatus, a relatively flat slip holding receptacle, buffer members attached to the ends of the receptacle, one of said buffer members being rotatably mounted, a closure member hinged at one lateral edge of the receptacle, and a finger carried by said rotatable buffer member and engaging the adjacent end portion of the closure member to operate the same.

50 8. In a carrier for pneumatic dispatch apparatus, a relatively flat elongated and rectangular slip holding receptacle, buffer members attached to the ends of the receptacle, one of said buffer terminal members being rotatably mounted, a closure member hinged to one lateral edge of the receptacle, a finger carried by said rotatable terminal member and engaging the under surface of the adjacent end of the closure member, and spring means tending to move the closure member to closed position.

65 JAMES G. MACLAREN.
